CLAIM

The ornamental design for an Ez pass holder, as shown and described.

DESCRIPTION

FIG. 1 is a front perspective view of a Ez pass holder;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a front perspective view of another example thereof;
FIG. 10 is a rear perspective view thereof;
FIG. 11 is a front view thereof;
FIG. 12 is a rear view thereof;
FIG. 13 is a left side view thereof;
FIG. 14 is a right side view thereof;
FIG. 15 is a top view thereof; and,
FIG. 16 is a bottom view.

The broken lines in the drawings illustrate the portions of the Ez pass holder, which form no part of the claimed design.
